UNITED STATES PATENT OFFICE.

JOSEPH PIPES, OF GUEYDAN, LOUISIANA.

COMBINED CHURN AND CLOTHES WASHER.

Application filed March 20, 1919. Serial No. 233,706.

To all whom it may concern:

Be it known that I, JOSEPH PIPES, a citizen of the United States, residing at Gueydan, in the parish of Vermilion and State 5 of Louisiana, have invented a new and useful Combined Churn and Clothes Washer, of which the following is a specification.

It is the object of this invention to provide a device which, at the will of an operator, 10 may be used either as a churn or as a clothes washer, novel means being provided for mounting the receptacle for rotation and novel means being provided for operating the pounder.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, with- 25 in the scope of what is claimed, changes in the precise embodiment of the invention shown can be made without departing from the spirit of the invention.

In the accompanying drawings:—

30 Figure 1 shows in vertical section, a device constructed in accordance with the invention, parts appearing in elevation; Figure 2 is a top plan; Figure 3 is a top plan of the rotatable platform or table; and Figure 4 is a section of the table.

In carrying out the invention there is provided a support denoted generally by the numeral 1. The support 1 includes a lower rectangular frame 2 and an upper rectangular frame 3 connected by corner posts 4. Posts 4 at the front and the back of the support 1 are united by cross bars 5 located between the frames 2 and 3. Retainers 6, which may be strips, connect the cross bars 45 5 with the end portions of the lower frame 2. Mounted on the end members of the lower frame 2 is a lower platform 7. An upper platform 8 is mounted on the cross bars 5. The ends of the platforms 7 and 50 8 are disposed between the retainers 6, and, consequently, the platforms cannot move crosswise. The lower platform 7 is provided on its lower surface and at its ends with cleats 9, which, coacting with the end 55 portions of the lower frame 2, prevent the

platform 7 from moving endwise. Similarly, the upper platform 8 is supplied on its lower surface and at its ends with cleats 10, which prevent the platform 8 from moving endwise. It will be seen that, although 60 the platforms 7 and 8 are removably mounted on the support 1, they cannot move, either transversely or longitudinally. A thrust bearing 11 is mounted on the lower platform 7 and is supplied with a plurality 65 of seats 12, spaced apart longitudinally of the thrust bearing. A bearing 14 is mounted on the upper platform 8 and is supplied with a plurality of openings 15, alined vertically with the seats 12 of the thrust bearing 11. Standards 16 connect the frames 2 and 3 of the support 1, at the rear end of the support and project above the upper frame, 3. The standards 16 are united intermediate their ends by a tie plate 17. 70

At their upper ends, the standards 16 carry transverse guides 18, between which the ends of a carrier 19, preferably in the form of a bar, are mounted, so that the carrier may be adjusted horizontally, transversely 80 of the standards 16.

The standards 16 are supplied with a plurality of openings 20, and there are similar openings in the ends of the carrier 19. In any of the openings 20, retainers 21 may be 85 mounted, to hold the carrier 19 in place, after the same has been adjusted horizontally.

The numeral 22 marks a fulcrum member having a stem 23 mounted in the carrier 19 intermediate the ends of the carrier. There are a plurality of transverse openings 24 in the stem 23 of the fulcrum member 22, and in any of these openings, a securing device 25, such as a bolt, mounted in the carrier 19, 90 may be received. Subsequently, the fulcrum member 22 may be adjusted vertically. The numeral 26 marks a lever, pivotally supported intermediate its ends, as indicated at 27, on the fulcrum member 22. A pair of strips 28, constituting a plunger, are disposed on opposite sides of the forward end of the lever 26, and are pivoted thereto, as indicated at 29. The strips 28 are supplied with a plurality of openings 30, to permit a vertical adjustment of the strips with respect to the forward end of the lever 26. Between the lower ends of the strips 28 is received a reduced neck 31 of a post 32 constituting a 100 part of a cruciform body 33, the body 33 and 105 32 being secured to the lever 26. Between the lower ends of the strips 28 is received a reduced neck 31 of a post 32 constituting a 110 part of a cruciform body 33, the body 33 and

the post 32 forming a pounder. The body of the pounder and the post thereof may be connected by braces 34. Securing elements 35 connect the reduced neck 31 of the 5 pounder with the strips 28.

The numeral 36 denotes a horizontal table, which may be of open cruciform outline, the arms of the table carrying transverse bars 37 constituting supports for a tub or other 10 receptacle 50. The central portion of the table 36 carries a post 38 including a reduced stem 39. The stem 39 is journaled for rotation in the bearing 14, the lower end of the stem being supported on the thrust bearing 15 11. Since there are a plurality of openings 15 in the bearing 14, and corresponding seats 12 in the thrust bearing 11, the table 36 may be adjusted transversely, carrying with it, in a horizontal adjustment, the tub 50.

20 In practical operation, when the lever 26 is operated, the pounder will operate in the receptacle 50, it being possible to rotate the receptacle along with the table 26 which is journaled, by means of the stem 29 in the 25 bearings 14 and 11 of the support 1. It is to be observed that, since the bearings 14 and 11 are provided respectively, with a plurality of openings 15 and with a plurality of seats 12, the table 36 may be adjusted in a 30 horizontal direction, toward and away from the standards 16, so as to accommodate receptacles of different sizes. By mounting the pivot element 29 in the openings 30 of the strips 28, the pounder may be adjusted 35 vertically with respect to the forward end of the lever 26 and with respect to the tub 50. It is possible to slide the carrier 19 forwardly and backwardly between the guides 18 and to hold the carrier in place by means of 40 the retainers 21, thus shifting the fulcrum member 22 horizontally. The fulcrum member 22 may be raised and lowered, the stem 23 of the fulcrum member moving vertically in the carrier 19, the securing device 25 co- 45 operating with any selected opening 24 in the stem 23. It may be noted that the lever 26 is to slide with a plurality of openings 51, in any of which the pivot element 27 may

be mounted, thereby to vary the length of the respective end portions of the lever 26. 50

Generally considered, the device is so constructed that it may be adapted readily to tubs 50 of different diameters,

If desired, the platforms 7 and 8 may be removed, thereby making it possible to place 55 a relatively tall receptacle within the contour of the frames 2 and 3. When the device is used as a churn, the pounder shown in the drawings will, of course, be replaced by a dasher of suitable construction (not 60 shown). Further, the tub 50 will of course be replaced by a churn body of proper configuration and shape.

Having thus described the invention, what 65 is claimed is:—

1. In an apparatus of the class described, a support having a standard rising therefrom, a table mounted for adjustment toward and away from said standard, a lever fulcrumed intermediate its ends on said standard and adjustable longitudinally thereon, and a pounder carried by said lever and vertically adjustable theron, the adjustment of said lever and the table adapting the apparatus for use in connection with 70 vessels of different diameters. 75

2. In an apparatus of the class described, a supporting structure, a standard rising therefrom, a carrier mounted on said standard for adjustment laterally relative thereto, a member mounted for vertical adjustment on said carrier, a lever fulcrumed intermediate its ends on said member and adapted for longitudinal adjustment thereon; a plunger depending from one end of said 85 lever, the adjustment of said lever and table adapting the apparatus for use with vessels of different sizes. 80

In testimony that I claim the foregoing as my own, I have hereto affixed my signature in the presence of two witnesses. 90

JOSEPH PIPES.
